(57) CLAIM

The ornamental design of a tongue scraper, as shown and described.

DESCRIPTION

FIG. 1 is a side view of a tongue scraper showing my new design;

FIG. 2 is a side view thereof, opposite that shown in FIG. 1;

FIG. 3 is a left end view thereof;

FIG. 4 is a fragmentary left end view thereof, with a portion of the end removed to show the bristles; and,

FIG. 5 is a bottom plan view thereof, the top plan view being a mirror image thereto.
